United States Patent Office.

E. B. REQUA, OF JERSEY CITY, NEW JERSEY.

Letters Patent No. 75,646, dated March 17, 1868.

IMPROVEMENT IN BALANCE-VALVES.

The Schedule referred to in these Letters Patent and making part of the same.

TO ALL WHOM IT MAY CONCERN:

Be it known that I, E. B. REQUA, of Jersey City, in the county of Hudson, and State of New Jersey, have invented a new and improved Steam-Valve; and I do hereby declare that the following is a full, clear, and exact description thereof, which will enable others skilled in the art to make and use the same, reference being had to the accompanying drawing, making a part of this specification, in which—

Figure 1 represents a longitudinal vertical section of my invention, taken in the plane indicated by the line $x'x$, fig. 2.

Figure 2 is a horizontal section of the same, the line $y'y$, fig. 1, indicating the plane of section.

Similar letters of reference indicate like parts.

This invention relates to a double balance-valve, the two valves of which are so arranged that they work one opposite to the other, and that the pressure of the steam on one valve is perfectly balanced by that on the other valve.

The nature of my invention, and its peculiar advantages, will be readily understood from the following description.

A represents a shell, made of cast iron, or any other suitable material. This shell is interposed between the supply-pipe of a steam-cylinder, or similar device, and its interior is divided off in two compartments, a b , by a horizontal partition, B, one end of which turns down and the other up, so as to close the compartment a at one end and the compartment b at the opposite end, and allow the compartment a to communicate freely with the induction-opening a^* of the shell, whereas the compartment b communicates freely with the eduction-opening b^* , or *vice versa*. The partition B is provided with two valve-seats, c c' , which are bevelled off in opposite directions, one being upright and the other reversed, as clearly shown in fig. 1 of the drawing. C C' are the valves, which correspond to the seats c c' , the valve C being fitted in from below, and the valve C' from above. An aperture, d , in the shell, which is closed by a screw-plug, D, gives a chance to introduce the valve C, and the valve C' is introduced through an aperture, e , in the top, which is closed by a screw-plug, E', and this plug serves at the same time as the stuffing-box for the stem f' of the valve C'. Said stem extends from both sides of the valve, and its lower end is stepped into a socket, g' , cast solid with or otherwise formed at the proper spot in the shell. By means of this step the valve C' is guided while grinding it in, and the operation of grinding is thereby considerably facilitated. The stem f of the valve C is stepped into a socket, g , formed in the centre of the screw-plug D, and it extends upward through the stuffing-box E, so that, in order to grind this valve in its seat, the plug D has to be removed, and during the operation of grinding, the stuffing-box E forms the guide to keep the valve in the proper position. The valve-stems f f' connect, by rods or pitmen g g' , with the opposite ends of a working-lever, F, the fulcrum-pin h of which has its bearings in the forked end of a standard or column, G, rising from the shell A. A hand-lever, H, which is firmly connected to one end of the fulcrum-pin h , serves to open and close the valves C C', and this hand-lever is provided with a circular slot, i , to catch over the stud j , which projects from the standard G, and which is furnished with a thumb-nut, k , whereby the hand-lever can be held in any desired position.

In order to be able to adjust the two valves so that they will close simultaneously, it is indispensable to have one or both of the pitmen g g' adjustable. In the drawings, I have represented the pitmen g , being adjustable by making it in two parts, one of which is provided with a right-handed and the other with a left-handed screw-thread, screwing into the barrel-nut l . If the valve C' is firmly closed, the valve C can be readily brought up to its seat by turning the barrel-nut in the proper direction, and if the valve C should close in advance of the valve C', the barrel-nut has to be turned back until both valves close precisely at the same moment. The hand-lever H may either be operated by hand, or it may be connected by the governor, or to the eccentric or other mechanism used for opening or closing the steam-valve, according to the function in which my valve may be employed. It may either be used in place of an ordinary stop-cock, or of a water-trap, or in place of the throttle or governor-valve, or in place of the slide-valve. It operates perfectly easy and independent of the pressure of the steam, the pressure on one valve being perfectly balanced by that on the other. It requires very little packing, and said packing is easily kept tight.

It is obvious that my valve may be equally used for hot-air engines, or, in fact, in any position where a stop-valve is used.

I am aware that the valve-chambers of governor-valves for steam-engines have been divided into two compartments and two valves, so arranged that an equal pressure of steam is made to act on each valve, thereby equally balancing them, but as this forms no part of my invention, I do not claim it; but having thus described my invention,

I claim as new, and desire to secure by Letters Patent—

1. The adjustable pitman *g*, in combination with the working-lever *F*, shell *A*, and valves *C C'*, constructed and operating as and for the purpose herein shown and described.
2. The arrangement of the slotted hand-lever *H* and thumb-nut *K* with relation to the working-lever *F*, adjustable valve-stems, and valves *C C'*, as herein described for the purpose specified.

E. B. REQUA.
